DESIGN FOR A PHONOGRAPH RECORD HOLDING SPINDLE

Willard J. Faulkner, Chicago, Ill.

Application August 21, 1943, Serial No. 110,976

Term of patent 14 years

(Cl. D26—14)

To all whom it may concern:

Be it known that I, Willard J. Faulkner, a citizen of the United States and a resident of Chicago, in the county of Cook and State of Illinois, have invented a new, original, and ornamental Design for a Phonograph Record Holding Spindle, of which the following is a specification, reference being had to the accompanying drawing, forming a part thereof.

Fig. 1 is a front elevational view of a phonograph record holding spindle embodying my new design;

Fig. 2 is a side elevational view taken thereof.

I claim:

The ornamental design for a phonograph record holding spindle, as shown.

WILLARD J. FAULKNER.
